UNITED STATES PATENT OFFICE

168,255

BATTERY SERVICE JUG

Robert B. Edelmann, Chicago, Ill., assignor to E. Edelmann & Company, Chicago, Ill., a corporation of Illinois

Application March 3, 1952, Serial No. 18,761

Term of patent 3½ years

(Cl. D58—25)

To all whom it may concern:

Be it known that I, Robert B. Edelmann, a citizen of the United States, and a resident of the city of Chicago, county of Cook, State of Illinois, have invented a new, original, and ornamental Design for Battery Service Jug, of which the following is a specification, reference being had to the accompanying drawing, forming a part thereof, in which:

Figure 1 is an isometric view of a battery service jug showing my new design, and

Figure 2 is a top plan view of the battery service jug shown in Figure 1.

I claim:

The ornamental design for a battery service jug, substantially as shown.

ROBERT B. EDELMANN.
